[57] CLAIM

The ornamental design for a water carafe, as shown and described.

DESCRIPTION

FIG. 1 is a top, front, and right side perspective view of a water carafe showing my new design;

FIG. 2 is a left side elevational view thereof;

FIG. 3 is a front elevational view thereof;

FIG. 4 is a rear elevational view thereof;

FIG. 5 is a bottom plan view thereof;

FIG. 6 is an exploded perspective view thereof with a fragment of the cover being omitted for sake of illustration; and

FIG. 7 is a sectional view thereof taken on line 7—7 of FIG. 1.

Fig. 3
